(57) **CLAIM**

The ornamental design for a dual coil fitting, as shown and described.

DESCRIPTION

FIG. 1 is a perspective view of the fitting;

FIG. 2 is a typical front view of the fitting;

FIG. 3 is a typical side view of the fitting;

FIG. 4 is a bottom view of the fitting;

FIG. 5 is a top view of the fitting;

FIG. 6 is a perspective view of a second embodiment of the fitting;

FIG. 7 is a typical front view of the second embodiment of the fitting;

FIG. 8 is a typical side view of the second embodiment of the fitting;

FIG. 9 is a bottom view of the second embodiment of the fitting; and

FIG. 10 is a top view of the second embodiment of the fitting.
